UNITED STATES PATENT OFFICE.

FRANK M. BROOKS, OF BROOKLYN, NEW YORK.

GAS-CHECK FOR BUNSEN OR SIMILAR BURNERS.

SPECIFICATION forming part of Letters Patent No. 700,893, dated May 27, 1902.

Application filed December 11, 1901. Serial No. 85,457. (No model.)

To all whom it may concern:

Be it known that I, FRANK M. BROOKS, a citizen of the United States, and a resident in the borough of Brooklyn, city of New York, county of Kings, State of New York, have invented a new and useful Improvement in Gas-Checks for Bunsen or Similar Burners, of which the following is a specification, reference being had to the accompanying drawings, in which—

Figure 1 illustrates an elevation of the Bunsen tube. Fig. 2 illustrates a vertical sectional view. Fig. 3 illustrates an elevation of the cap or upper part of the gas-check. Fig. 4 illustrates an elevation of the bottom part of the gas-check. Fig. 5 illustrates a vertical sectional view of the gas-check in its position when there is substantially a full flow of the gas.

In burners of this class as heretofore constructed the checking of the gas has been accomplished in various ways, all of them, so far as I am aware, more or less complicated and involving a greater or less amount of dis-

organization of the burner in order to effect the adjustment, and usually the immediate means for reducing or increasing the flow has been the employment of a check having a hole in it of a greater or less diameter through which the gas passes to the point of combustion. Consequently if the hole in the check or similar device be too big it is necessary to disorganize the apparatus and supply a new one having a smaller hole, and the same is true if the hole is too small, not permitting sufficient flow of gas, excepting that it is possible to bore out the hole to make it larger, which under ordinary circumstances is impracticable.

Under my present invention the flow can be exactly adjusted as preference or necessity requires without disorganizing the burner in the least and in a most easy, quick, and effective manner.

The construction of the apparatus is as follows:

A is the burner-tube. B B are the air-holes therein.

C is the check, which threads into the bottom of the tube, as shown. It is interiorly threaded, as at D, for attachment to the ordinary gas bracket or jet.

E is a hollow stem or part which projects upwardly from the check C, and it is threaded exteriorly, as at F, for the reception of a 55 hollow cap G, which is perforated, as at H, at its upper end and is provided with a milled flange G'. The opening I through the stem E terminates in two lateral openings K K into the chamber within the cap G, and above 60 these openings there is a conically-shaped terminal L on the stem E, which is adapted to fit and close the opening H in the cap G after the manner of the well-known needle-valve.

A special feature of the invention is the fact that the parts are so proportioned that when properly assembled, as shown in Figs. 1 and 2, the flange G' of the cap G is located adjacent to the air-holes B, so that the end 70 of a pencil or a pin or any other similar article or utensil may be inserted through the air-holes and by pressure against the milled flange turn the cap G, running it up or down, as occasion requires, thus regulating the flow 75 of gas.

It will be obvious to those familiar with this art that modifications may be made in the details of construction of the parts without departing from the essentials of the invention. I therefore do not limit myself to the details shown.

Having described my invention, I claim—

1. In a Bunsen burner the combination of a burner-tube provided with air-holes, a hollow check adapted to close the end below the air-holes and having an upwardly-extending threaded and hollow stem provided with a needle-valve, a gas-regulating cap embodying a seat for the needle-valve threaded to 85 the stem and a flange on the cap, the flange being accessible from the exterior through the air-holes in the tube, whereby the supply of gas may be regulated without affecting the supply of air.

2. In a Bunsen burner the combination of a burner-tube provided with air-holes, a hollow check adapted to close the end of the tube below the air-holes, passage-ways for the gas through the check, a needle-valve 100 extending upwardly from the check, a gas-regulating cap threaded to the check embodying a seat for the needle-valve, said cap being located opposite the air-holes in the tube

whereby it may be actuated through them, and the supply of gas regulated without affecting the supply of air.

3. In a Bunsen burner the combination of
5 a burner-tube provided with air-holes, a hollow check adapted to close the end of the tube
below the air-holes and provided with threads
for attachment to a gas-fixture, an upwardly-
extending threaded stem provided with pas-
10 sage-ways for the gas and a needle-valve, a
perforated gas-regulating cap threaded to
the stem and adapted to inclose the gas-pas-
sages in it and provided with a seat for the
needle-valve through which the gas escapes

into the burner-tube, the parts being so pro- 15
portioned and arranged that when assembled
the cap is accessible and may be manipulated
through the air-holes in the tube for cutting
off the supply of gas without affecting the
supply of air.

20 In testimony whereof I have signed my
name to this specification in the presence of
two subscribing witnesses.

FRANK M. BROOKS.
